CLAIM

The ornamental design for an automotive light bar, as shown and described.

DESCRIPTION

FIG. 1 is a perspective view of an automotive light bar showing my new design;
FIG. 2 is a top plan view of an automotive light bar;
FIG. 3 is a front view of an automotive light bar;
FIG. 4 is a rear view of an automotive light bar;
FIG. 5 is a left side elevational view of an automotive light bar, the right side is a mirror image thereof; and,
FIG. 6 is a bottom plan view of an automotive light bar. The automobile is shown in broken lines in FIG. 1 for illustrative purposes only and forms no part of the claimed design.
